UNITED STATES PATENT OFFICE.

SAMUEL E. SPERRY, OF WOODHAVEN, NEW YORK, ASSIGNOR TO INTERTYPE CORPORATION, OF BROOKLYN, NEW YORK, A CORPORATION OF NEW YORK.

MOLD DISK FOR TYPOGRAPHICAL MACHINES.

Application filed April 2, 1925. Serial No. 20,261.

The present invention relates to improvements in the casting mechanism of typographical machines, and especially those of the linotype class, an example of which is set forth in the patent to O. Mergenthaler, No. 436,532, granted September 16, 1890.

The primary object of the invention is to provide a novel and improved mold disk for machines of this class whereby the component parts of the molds thereon are securely held in their proper operative relationship without undue strain on the mold disk, and the mold disk is strengthened or reinforced so that it effectually resists stresses exerted thereon incident to the operation of the machine and which tend to distort it and to displace the mold parts.

Heretofore it has been the practice, in typographical machines of the linotype class, to secure the mold cap and liners in proper relation to the mold body by clamping screws which engage the ends of the mold cap, and in order to prevent outward springing of the middle of the mold cap, set-screws have been employed which were fitted into the peripheral portion of the mold disk and abutted against the mold cap intermediate of its length. However, in order to apply the molds to the mold disk, peripheral portions of the mold disk have been cut away to accommodate the molds, and in attempting to apply four molds to the mold disk in order to increase the range of usefulness of the machine to meet demands, it has been found that the cutting away of the mold disk to accommodate such a number of molds weakens the mold disk to such an extent that the support afforded the set-screws is not sufficiently rigid to secure to hold the mold cap and liners firmly in place, and the consequent weakening of the mold disk renders it subject to strain and distortion under the stresses imposed upon it incident to the ejection of the cast slugs from the mold, and other operations of the machine.

The present invention provides a mold disk which enables four molds to be applied thereto and the caps and liners thereof firmly and securely held in place, and it enables the mold disk to effectually withstand the stresses imposed thereon without strain or distortion.

To these and other ends, the invention

consists in certain improvements and combinations and arrangements of parts, all as will be hereinafter more fully described, the features of novelty being pointed out particularly in the claims at the end of the specification.

In the accompanying drawing:—

Figure 1 is a face view of a mold disk adapted for use in typographical machines of the linotype class, the mold disk being constructed in accordance with the preferred embodiment of the present invention;

Figure 2 represents a section taken on the line 2—2 of Figure 1; and

Figure 3 represents a cross-section taken radially through the rim of the mold disk and showing another embodiment of the invention.

The present invention provides a mold disk which enables the parts of the mold or molds thereon to be held in place with greater security than heretofore and it provides a mold disk which is reinforced or strengthened so that it is enabled to withstand stresses imposed upon it substantially without strain or distortion. The improved mold disk may be employed as a carrier for one or more molds, but the mold disk is particularly useful where a large number of molds, three or four for example, are to be employed. The preferred embodiment of the invention is shown in the accompanying drawing and will be hereinafter described in detail, but it is to be understood that the invention is not restricted to the precise construction shown, as equivalent constructions are contemplated and such will be included within the scope of the claims.

In the present instance, the mold disk comprises a hub 1 which may be adapted to be mounted for rotation on the forward end of the mold slide such as that commonly employed in machines of the linotype class; 2 designates the web portion of the mold disk, and 3 designates the rim of the disk which is usually provided with gear teeth 4 which in machines of the linotype class mesh with a pinion which serves to rotate the mold disk at appropriate periods in the operation of the machine to bring the mold which is in use to the casting point, and after the cast has been made, to carry the mold containing the slug cast therein to the ejecting position where an ejector operates on the slug to

eject it from the mold, after which the mold disk rotates to restore the mold to the casting position.

The molds are mounted on the face of the 5 mold disk, each mold usually comprising a body 5, liners 6 which determine the thickness and length of the slug to be cast in the mold, and a cap 7 which rests on the liners and closes the top of the mold cavity. A 10 portion of the mold body and the mold cap are usually let into a recess 8 which is formed in the peripheral portion of the web 2 of the disk. The body 5 of each mold is rigidly fixed to the disk as by screws 9^a but 15 the mold cap 7 and the liners 6 are removable so that liners of different thickness or of different lengths may be interposed between the mold body and cap to accord with the thickness and length of the type bars or 20 slugs to be cast in the mold.

Usually the mold cap, liners and mold bodies have been held altogether or in proper relationship by clamping screws at the ends of the body and cap, and in order to hold the mold cap, liners and mold body from 25 outward displacement under the forces applied incident to the ejecting or other operation of the machine, compression screws have been fitted in the outer or peripheral 30 portion of the disk to bear at their inner ends against the top of the mold cap, substantially as shown, for example, in the patent to T. S. Homans, No. 1,116,279, granted November 3, 1914, such screws being adjustable 35 so that liners of different thicknesses could be accommodated between the mold cap and body and thus permit other liners to be substituted; and in using such screws in mold disks to which only one or two molds 40 were applied, these compression screws could be set up with sufficient pressure against the top of the mold cap to firmly hold the cap and liners in fixed relation to the mold body. However, it has been found that if such 45 compression screws were applied to a mold disk of the kind usually employed in machines of the linotype class and to which a large number of molds, four for example, has been applied, the portions of the periphery of the disk through which these screws pass would 50 become strained and distorted as a result of the outward reaction from the pressure of the screws and of the stresses imposed upon the mold and tending to displace the mold 55 cap outwardly incident to the ejection of the cast slug from the mold during the operation of the machine, owing to the cutting away and consequent weakening of the mold disk in adapting it to receive such a number 60 of molds, and hence, the screws would fail to lock the mold cap and liners in place with the requisite rigidity to insure the maintenance of the correct relationship between the component parts of the mold.

65 The present invention provides a rein-

forcement for the mold disk whereby it is enabled to effectively resist or sustain the reaction produced by the firm setting up of the compression screws against the mold cap and to withstand stresses imposed upon the mold during the ejecting or other operations of the machine, and which tend to displace the mold cap outwardly or to distort the disk. This reinforcement comprises a circumferentially continuous band which 70 encircles the rim of the disk and provides a substantially distortionless support for the mold securing screws. Preferably, and as shown in the present instance, the reinforcement comprises a band 11 composed of steel or other metal or material possessing the requisite strength, this steel band being shrunk or forced onto the disk with sufficient firmness to become a unitary part of the 75 disk, and an edge of the band overhangs the caps of the molds so that the overhanging portion may receive the screws 9 and 10 and position these screws so that they will bear on the tops of the mold caps. In applying a reinforcing band to the mold disk, the latter may be constructed in the usual way except that about one-half of the width of the gear or driving teeth 4 are omitted or cut away to provide a recess 12 which surrounds the rim of the disk and provides a seat for 80 the reinforcing band. It will be understood that the width of the teeth on the usual driving pinion which meshes with the peripheral gear teeth 4 of the mold disk will be correspondingly reduced to conform substantially 85 with the reduced width of the teeth 4 and to thus provide clearance for the reinforcing band 11. By properly proportioning the interior bore of the reinforcing band 11 and the diameter of the recess or seat 12 to produce 90 tension upon the reinforcing band as the result of the shrinking or forcing of this band upon the disk, the outward reaction produced on the compression screws 9 and 10 while locking or clamping the mold cap and liners in place will be effectively resisted by the contracting tendency of the reinforcing band, and furthermore, the reinforcing band which, in effect, becomes a part of the 95 rim of the mold disk adds stiffness and 100 strength thereto and thereby prevents strain or distortion of the mold disk, which is usually composed of cast iron, under the stresses which are applied to it during the 105 ejection of the slugs or other operations of the machine. Instead of constructing the reinforcing band as a separate part and applying it to the mold disk, this reinforcing band may be cast or otherwise formed as an 110 integral part of the rim of the mold disk as 115 shown in Fig. 3, and in that case, the increased thickness of the portion of the mold disk rim occupied by the reinforcing band 120 designated 11^a will provide a support of 125 sufficient strength and rigidity for the mold 130

cap compression screws, and it will stiffen the rim sufficiently to resist forces tending to strain or distort the mold disk. Where the reinforcing band is cast or formed as an integral part of the mold disk, the gear teeth 4^a on the periphery of the disk may be milled in substantially the usual way except that they would be of reduced width, as is the case where the separately formed reinforcing band is applied to the disk, and the gear teeth would run out instead of through the integrally formed reinforcing band, substantially as shown in Fig. 3.

By providing the rim of the mold disk with a circumferentially continuous or uninterrupted band, a part of which lies in the plane of or overhangs the top of the mold cap, and threading the mold cap compression screws through this overhanging part of the band, the compression screws may be set up to the extent required to lock the mold cap and liners to the mold body with sufficient firmness to resist forces tending to displace the cap, as the reinforcing band serves to effectively sustain the reaction of the screws so that the mold disk will not become distorted in consequence of such reaction; and the stiffening effect of the reinforcing band will strengthen the rim or peripheral portion of the mold disk sufficiently to enable it to sustain, without strain or distortion, the stresses imposed upon it incident to the ejection of the cast slug from the mold or any of the other usual operations which take place.

The invention is especially useful as a means to enable a large number of molds, three or four, for example, to be employed on the mold disk, as it adds to the mold disk sufficient strength and rigidity to offset the substantial weakening of the disk by the cutting away thereof to accommodate such a large number of molds, but the invention may also be utilized as a means for sustaining the reaction of the mold cap compression screws and for preventing distortion of the mold disk under the strains imposed upon it when one or more molds are used.

I claim as my invention:—

50 1. A mold disk for typographical machines having driving teeth which occupy

a part of the width of its rim and a circumferentially-continuous reinforcing band which encircles its rim and occupies another portion of its width.

55

2. A mold disk for typographical machines having driving teeth which occupy a part of the width of its rim, said driving teeth being cut away to form a recess which occupies another part of the rim, and an encircling reinforcing band seated in said recess.

60

3. A mold disk for typographical machines having a mold set in its face and having a circumferentially-continuous reinforcing band which encircles the outer periphery of its rim and part of which overhangs the mold, and mold-locking means supported by the overhanging part of said band.

65

4. A mold disk for typographical machines having a mold recessed in its face and having a circumferentially-continuous reinforcing band encircling the outer periphery of its rim, part of said band occupying a position opposite to the mold cap, and mold-locking screws fitted in said part of the band and bearing against the mold cap.

70

5. A mold disk for typographical machines having a mold recessed in its face and having driving teeth occupying part of the width of its rim, said teeth being cut away to form an encircling recess which occupies another part of the width of the rim, a circumferentially-continuous band seated in said recess, part of said band overhanging the top of the mold, and mold locking means supported by said overhanging part of the band.

75

6. A mold disk for typographical machines having a mold on its face, and having a reinforcing band, a portion of the width of which overhangs the top of the mold and extends continuously around the outer side of the circumference of the rim of the disk, and mold locking means sustained by the overhanging portion of the band and operative to exert inward compression on the cap of the mold.

80

In testimony whereof I have hereunto set my hand.

SAMUEL E. SPERRY.
